UNITED STATES PATENT OFFICE.

ERNST BAARTH, OF STAUCHITZ, AND OTTO SPILGER, OF DÖBELN, GERMANY.

VEGETABLE-CUTTER.

SPECIFICATION forming part of Letters Patent No. 293,300, dated February 12, 1884.

Application filed March 23, 1883. (No model.)

To all whom it may concern:

Be it known that we, ERNST BARTH, of Stauchitz, and OTTO SPILGER, of Döbeln, in the Empire of Germany, citizens of Germany, 5 have invented certain new and useful Improvements in Vegetable-Cutting Machines, of which the following is a specification.

The nature of our invention consists in the arrangement of a number of knives side by side on a shaft, the ends of said knives passing through slots in a plate inserted in the face of the table, in which the same are guided and project a desired distance to cut the vegetable lengthwise before the usual stationary knife cuts the same in disks or thin slices; and, further, in the arrangement of a sliding plate placed upon the table and below the sliding box, whereby, according to the thickness of said plate, the thickness of the 15 disks or slices cut off by the stationary horizontal knife can be regulated.

In the accompanying drawings, Figure 1 is a front view of the machine, and Fig. 2 a back view. Figs. 3 and 4 are longitudinal 20 sections, and Figs. 5 and 6 cross-sections, of the same.

Similar letters represent similar parts in all the figures.

B is the table or bed of the machine, having side pieces, A A, in which guiding-grooves *i* and *f* are made. In the bed or table B the usual cutting-knife, M, is arranged, slightly diagonal across the width of the table.

K is a box moving in the grooves *f* of the side pieces, A, to receive the vegetable to be cut, and in which the same is moved back and forth over the table and the cutting-knife M. This box K is provided with a plate or piston, *d*, to press upon the vegetable and force the 35 same down upon the surface of the table, when, while passing the knife M, regular disks or pieces are cut off. The knife M is so arranged that it will generally cut the disks or pieces off the vegetable at the greatest thickness which may be desired, and the grooves *f* 40 guide the box K, so that its under side will just clear the edge of this knife M. If pieces or disks of a less thickness are to be cut, a sliding plate, S, of the desired thickness, is 45 inserted into the grooves *i* of the side pieces, A A, extending up to the surface of the knife M, and whereby, by regulating the thickness of said plate S, the thickness of the pieces, slices, or disks cut off from the vegetable can 50 be regulated.

Forward of the cutting-edge of the knife M a shaft, *g*, is arranged at the under side of the table B, to which a number of knives, *m*, are attached, projecting, when in an upright position, as shown in Fig. 3, above the surface 60 of the table B about as much as the edge of the knife M is arranged above the top surface of the table B. R is a plate inserted in the surface of the table B, flush with the same, and provided with slots *r*, through which the 65 ends of the knives *m* pass, and in which the same are guided sidewise. The vegetable in the box K, while passing these knives *m*, will be cut longitudinally at its bottom surface, and will then, when passing the knife M, be cut 70 off the desired thickness, producing thereby regular strips of a width corresponding to the distance the knives *m* are placed from each other. When these knives *m* are not to be used, the shaft *g* is turned so that the edges of 75 the knives *m* come below the top surface of the plate R, as shown in Fig. 4, when only the knife M will operate in the usual manner. The axis of the shaft *g* moves in suitable cavities made on the under side of the table B, 80 and is held in its place by sliding bolts *n*, by which arrangement this shaft *g*, with the knives *m*, is easily removed for the purpose of cleaning the same.

We do not claim the arrangement of a number of splitting-knives in a vegetable-cutter, operating in combination with the usual slicing-knife, broadly; but

What we claim as our invention, and desire to secure by Letters Patent, is—

1. In a vegetable-cutter, in combination with the table B, provided with a stationary knife, M, and sliding box K, a number of knives, *m*, attached side by side to a shaft, *g*, and the plate R, provided with slots or openings *r*, through which the ends of the knives *m* project, and in which the same are guided, the whole being arranged to operate substantially in the manner and for the purpose described.

2. In a vegetable-cutter, the sliding plate S, inserted between the table B and the sliding box K, in the manner and for the purpose described.

ERNST BAARTH.
OTTO SPILGER.
